SAFETY DEVICE FOR VERTICALLY MOVABLE DOORS

Maurice B. Zoll, Lynnwood, Lynnhaven, and Ervin R. Stallings, South Fairview, Va., assignors to The J. G. Wilson Corporation, Norfolk, Va., a corporation of Delaware

Filed Dec. 1, 1960, Ser. No. 72,967
8 Claims. (Cl. 20—19)

This invention relates to improvements in safety devices or catches to check the downward movement of vertically movable doors, in case of breakage of suspending cables or other accident which would otherwise allow the doors to fall.

An object of our invention is to provide a safety device for a vertically sliding door to prevent the latter from falling, with possible injury to personnel, if the counter-balancing mechanism thereof fails.

Another object of our invention is to provide a device of the character described which is not dependent on slots in a door guide, to receive teeth of a door-checking device, or a projection on a roller or catch-carrying member.

A further object of our invention is to provide a safety device of the character described in which the door-carrying cable is connected to the door-checking-pawl carrying shaft, as through a crank or arm thereon, rather than directly to the door itself or a member rigidly secured thereto.

A still further object of our invention is to provide, in an arrangement as above described, a support for a free end portion of the shaft lever or crank pin thereof, while said pin serves to support the door.

An additional object of our invention is to provide an improved construction for the lever or crank on the shaft of the device, whereby broaching is avoided by the substitution of a construction employing molten metal or solder, thereby facilitating and cheapening the manufacture of the device.

Another object of our invention is to provide, as the checking means for the door, a pawl shaped with respect to the guide channel and provided with a plurality of teeth disposed in a plane so that, after engagement of the first teeth, additional teeth are brought into play as the guide channel is indented and expanded by the pawl, as determined by the weight and velocity of the door at the time of the checking action.

A further object of our invention is to provide a safety catch in the form of a pawl, with teeth disposed along a straight line, so formed as to size and shape that, when the catch is released to effect a checking of the door, a desired wedging action between the pawl and channel of a guide rail occurs to stop descent of the door, with the employment of only a needed number of teeth which successively engage.

These and other objects and advantages will become apparent from the following detailed description when taken with the accompanying drawings. It will be understood that the drawings are for purposes of illustration and do not define the scope or limits of the invention, reference being had for the latter purpose to the appended claims.

In the drawings, wherein like reference characters denote like parts in the several views:

FIG. 1 is a fragmentary inside elevational view of one lower corner portion of a vertically slidable door with our safety device installed thereon.

FIG. 2 is a fragmentary horizontal sectional view on the line II—II of FIG. 1, in the direction of the arrows.

FIG. 3 is a fragmentary side elevational view of the structure illustrated in FIG. 1.

2

FIG. 4 is an elevational view of the lever or crank assembly of our device with associated hub and pin, illustrating the novel construction thereof.

FIG. 5 is an end elevational view of the structure illustrated in FIG. 4.

FIG. 6 is a perspective view of the parts forming the hub of the crank assembly, illustrated in FIGS. 4 and 5, prior to insertion of the inner non-circular portion into the hollow cylindrical portion thereof.

10 FIG. 7 is a side elevational view of the pin or shaft which carries the crank assembly of FIGS. 4 and 5, as well as the spring, roller, and pawl of FIGS. 1, 2 and 3. Referring to the drawings in detail, there is illustrated an embodiment of our invention designed to be used in connection with a vertically sliding door 11 of known construction. The door may be rigid or formed of a plurality of horizontally hinged or otherwise articulated sections. It is desirably provided at vertically spaced intervals with rollers 12 (only one of which is shown) 20 along both of its vertical edges, received in vertically-extending guide rails 13 (only one of which is illustrated) each having a channel 14.

Each guide rail 13 may have a vertically extending web 15 secured to the wall or casing 16 of the building with which the door is used, along a side of the door opening, as by a mounting bracket 17. A horizontally extending shaft (not shown) may be mounted above the door opening and provided with a pulley (not shown) for taking up or letting out a supporting cable 18. As an illustration of such a shaft and pulley for a supporting cable, see the Moler Patent No. 2,651,817, dated September 15, 1953.

The shaft may be power operated or, as illustrated in said patent, may have a helical spring wound therearound to counterbalance the weight of the door. Although only one supporting cable 18 is illustrated, it will be understood that we may have such a cable adjacent each vertical edge of the door and similar safety apparatus associated therewith. The counterbalancing construction is well known and so is not described in greater detail.

At least one lower corner portion of the door 11 carries a mounting plate 19. This plate serves to rotatably support a shaft or pin 21, as by being provided with outstanding bearing brackets 22 and 23. These brackets may be formed separately of the plate 19 and welded or otherwise secured thereto, or they may be slit therefrom and bent out, if so desired. They are desirably braced by receiving and having connected thereto a hollow cylindrical member or tube 24, which forms an elongated bearing for the shaft 21. The shaft 21 carries a release lever or crank assembly 25 which is non-rotatably mounted thereon as by having a hub 26 provided with a non-circular, desirably square, aperture 27, to snugly receive the corresponding non-circular or square end portion 28 of the shaft 21.

The lever assembly 25 is for economy desirably formed as illustrated in detail in FIGS. 4, 5, and 6. That is, the lever or arm portion 20 may be formed from a flat sheet or plate of metal, such as steel elongated in shape, desirably wider at its hub-adjacent end than at its free end and non-symmetrically shaped about its longitudinal axis, as illustrated in FIG. 5, thereby providing a desired increased clearance with respect to the plane of the door 11. The hub 26 of said assembly is formed as a hollow cylindrical metal portion or bushing 29 snugly fitted in a corresponding aperture laterally offset from said axis in the lever portion 20 and, in turn, snugly receiving a non-circular tubular metal member or bushing 31, desirably square in section. This member 31 may be formed peripherally continuous, as by pressing to shape a member of initially hollow cylindrical form. As an alternative, however, the

member 31 may be formed by bending a flat sheet or plate of metal, steel being an example, to the form illustrated, in which event there will initially be a break in its peripheral continuity, which is closed during a subsequent operation.

After forming the parts to the shapes illustrated in FIG. 6 and slipping the tubular member 31 inside the tubular member 29, these parts are then inserted in the correspondingly-formed hub aperture of the lever member 20, to make the assembly 25 illustrated in FIGS. 4 and 5. The parts are then secured together by suitable means, desirably silver solder or other metal 30 which is melted and run into the spaces between the exterior of the part 31 and the interior of the part 29, closing the peripheral break, if present, in the member 31, as well as similarly securing the parts 20 and 29. The lever or crank assembly 25 is then completed, as by inserting a pin 32 in a corresponding aperture 33 in the lever portion 20 remote from the hub 26 and welding or otherwise suitably connecting it to said lever portion.

After applying the hub 26 over the non-circular portion 28 of the shaft 21, the roller 12 is applied thereover, followed by the application of the safety catch or locking wedge or pawl 34. This means that the roller is freely rotatable on the cylindrical remnants 40 on the non-circular portion 28 of the shaft 21 between the crank assembly 25 and the pawl 34. This pawl has a corresponding non-circular or square aperture 35, snugly receiving the correspondingly-formed or squared portion 28 of the shaft 21. The pawl 34 may be of steel, case-hardened or otherwise provided with a hardened surface. It may be secured to the squared portion in any desired manner, as by a drive fit or by means of a set screw, not shown. If desired, the non-circular hole 35 may be provided by the use of a bushing non-circular in section (like the bushing 31, for example) and secured in place by molten metal as previously disclosed for the assembly 25, except that the use of a cylindrical bushing thereabout may be omitted. It is desirably shaped as illustrated in the drawings, which are to scale. Thus, an opposed pair of the straight sides of said hole 35 are desirably generally parallel to the plane of the surface carrying the teeth or end portion 36. That is, the distance of the toothed end portion 36 from the aperture 35, the angle of the plane, carrying the teeth, to the axis of the pawl 34 is as illustrated, when used with a guide rail 13 having a channel of the width illustrated.

By so constructing the pawl, upon release the same will turn counter-clockwise, from its full line position through an angle designated 37, to its position illustrated in dotted lines in FIG. 3, whereupon the first teeth 38 will biting engage the flange 39 of the guide. If the door 11 is at that time dropping at a slow rate of speed, these teeth 39 may be all that are needed to stop it. However, if more are needed, they successively come into play as the door descends and the other teeth are drawn toward the flange 39 as the pawl turns counter-clockwise as viewed in FIG. 3.

This biting action occurs, rather than a sliding of the pawl along the flange 39, by virtue of the relationship between the pawl 34 and the guide rail 13, as well as the fact that the pawl carries two parallel rows of desirably six teeth each, each tooth being shaped as a square pyramid with a sharp apex, said teeth rising from a face disposed at an angle of desirably 60° to the longitudinal axis of said pawl. It will be noted that at the time of engagement there is only a small angle between the toothed portion 36 and the flange 39, so that a strong wedging action occurs, tending to force an increasing number of teeth into locking engagement with the flange 39 as the biting or indenting is effected and the guide rail 13 expanded.

The means for biasing the pawl 34 into locking engagement with the guide rail 13, in the present embodiment takes the form of a helical spring 41. One end portion of said spring 41 is secured to the shaft 21, as by means of a pin 42 passing into an aperture 47 in an end

portion of said shaft and encircled by an end portion of the spring 41, and the other end of the spring is locked to the bearing bracket 22, as by passing through an aperture 43 therein and bent over therebeyond as at 44. After 5 the connection of the spring 41 to the pin 42 and the bracket 22 is effected, the spring is tensed, as by turning the pawl 34 clockwise, as viewed in FIG. 3, until the desired amount of torsional tension is imparted thereto.

This spring tension is maintained by connecting the 10 cable 18 to the pin 32, as by providing a grommet 45 around which the lower end portion of the cable 18 is wrapped and secured, and through which grommet said pin passes, as viewed most clearly in FIGS. 1, 2 and 3. In order to relieve the pin 32 of stress and prevent possible 15 bending thereof, as well as of the lever member 20, we provide a cable pin support 46, desirably in the form of an angular bracket. The base flange 49 of said bracket is secured to the door fixture 19 in any desired manner, and the outstanding flange 48 overlies the free end position of the pin 32 and provides an abutment therefor when said pin 32 is in uppermost position as viewed in FIGS. 1, 2 and 3.

In normal operation, the door 11 is raised or lowered by 20 operation of the cable 18. Said cable transmits force to the door, not only through the bracket 46, but also through the crank assembly 25, shaft 21, tube 24 and brackets 22 and 23, while the lever 20 extends straight up from its shaft 21. Upon failure of the cable 18, or of the associated counter-balancing mechanism, allowing said 25 cable to become slack, the shaft 21, crank assembly 25, and pawl 34 are allowed to quickly turn counter-clockwise, as viewed in FIG. 3, upon the descent of the door 11, under the action of the pre-stressed spring 41. This turning carries the pawl 34 from its normal full-line position to that indicated in dotted lines in FIG. 3, forcibly jamming the first teeth 38 thereof into the flange 39 of the guide rail 13, and starting to check the downward movement of the door.

40 This downward movement of the door will be entirely checked upon engagement of two or more teeth with the flange 39, depending on the velocity of descent at the time the pin is released, as well as on the tension initially applied to the spring 41, its strength, the weight of the door, the clearance provided between the roller 12 and the guide 45 rail 13, and the resiliency of the flanges of said rail.

After the door 11 has been stopped, it may thereafter be raised by hand and connected to a new cable, or to the old one if unbroken upon repair of the counter-balancing mechanism, whereupon the cable will again 50 draw the pawl 34 away from engagement with the flange 39 of the guide rail 13 and allow the door to be moved up or down in a normal manner, guided by the roller 12 and other rollers conventionally used but not here illustrated. Although the safety mechanism at only one 55 side of the door is illustrated, it will be understood that it may be duplicated at the other vertical edge of the door and associated with another operating cable.

From the foregoing disclosure it will be seen that 60 we have provided an improved safety mechanism for vertically sliding doors where an operating cable (or cables) normally supports (or support) the door through the safety mechanism itself, as well as through a door bracket cooperating with a part of said mechanism. The pawl 34 which stops the descent of the door, upon failure of the operating or counter-balancing mechanism is specially designed and shaped so as to gradually bring 65 in the number of teeth necessary to effect complete stoppage of the door, without the necessity of having slots 70 in the guide rail (or rails) to catch said teeth, and without the necessity of piercing said guide rail (or rails) or otherwise mutilating the mechanism, thereby obviating its reuse until repaired. Wedging action is obtained by 75 forming the pawl wedge-shaped, thereby avoiding the necessity of having a wedging projection on the carrying

roller opposite the point of engagement of the pawl with the guide rail.

Having now described our invention in detail in accordance with the patent statutes, those skilled in this art will have no difficulty in making changes and modifications in the individual parts or their relative assembly in order to meet specific requirements or conditions. Such changes and modifications may be made without departing from the scope and spirit of the invention, as set forth in the following claims.

We claim:

1. A lever and hub assembly comprising a flat sheet of metal elongated in shape and with one end portion having an aperture on its longitudinal axis, the other end portion being wider than said axis-apertured end portion, an aperture laterally offset from said axis and formed in said wider end portion, a hollow cylindrical hub fitting the laterally offset aperture, a non-circular bushing fitted into the hollow of said hub and with corners engaging the inner surface thereof, and metal integrating the parts by solidification from the molten state while disposed between said bushing, hollow cylindrical hub and flat sheet.

2. A safety device for a vertically movable door, associated with a vertically extending guide rail having a channel and disposed along a vertical edge of the door, said device comprising a shaft, said shaft having one end portion non-circular in section, means on said door for rotatably supporting said shaft so that it projects laterally into the channel of said guide rail, a pawl movable between door releasing and door checking positions in said channel and operably secured to said shaft, spring means biasing said shaft rotatably so as to tend to move said pawl into door-checking position in said channel, a lever having a hub with an aperture formed to correspond with the non-circular portion of said shaft, in which is non-rotatably fitted said non-circular shaft portion, said lever and hub assembly comprising a flat sheet of metal elongated in shape and with one end portion having an aperture on its longitudinal axis, the other end portion being wider than said axis-apertured end portion, an aperture laterally offset from said axis and formed in said wider end portion, a hollow cylindrical hub fitting the laterally offset aperture, a non-circular bushing fitted into the hollow of said hub and with corners engaging the inner surface thereof, metal integrating the parts by solidification from the molten state while disposed between said bushing, hollow cylindrical hub and flat sheet, and a cable secured to said lever to, as long as it is taut, lift and sustain said door, resist the door-checking action of said spring means, and thereby prevent the pawl from being moved by said spring means to door-checking position.

3. A safety device for a vertically movable door associated with a vertically extending guide rail having a channel and disposed along a vertical edge of the door, said device comprising a shaft, means on said door for rotatably supporting said shaft so that it projects laterally into the channel of said guide rail, a pawl movable between door-releasing and door-checking positions in said channel and operably secured to said shaft, spring means biasing said shaft rotatably so as to tend to move said pawl to door-checking position in said channel, a lever secured to said shaft, a pin projecting laterally from said lever, a cable secured to said pin, and a support projecting from said door and overlying a free end portion of said pin, to form a pin abutment for relieving said pin of strain and transmitting force between said cable and said door to, as long as said cable is taut, vertically

lift and sustain said door through said lever and shaft while said lever extends straight up therefrom, resist the door-checking action of said spring means, and thereby prevent the pawl from being moved by said spring means to door-checking position.

- 5 4. A safety device for a vertically movable door, associated with a vertically extending guide rail having a channel and disposed along a vertical edge of the door, said device comprising a shaft with one end portion non-circular in section, means on said door for rotatably supporting said shaft so that it projects laterally into the channel of said guide rail, a pawl movable between door-releasing and door-checking positions in said channel and operably secured to said shaft, spring means biasing said shaft rotatably so as to tend to move said pawl to door-checking position in said channel, a lever as a flat sheet secured to said shaft, the non-circular end portion of said shaft fitted in a correspondingly-formed aperture in said lever, the non-circular portion of said lever being formed by fitting a hollow non-circular bushing within a hollow cylindrical hub portion and securing the three parts together by the use of metal solidified from the molten state while disposed between said flat sheet, hub portion and bushing, and a cable secured to said lever to, as long as it is taut, vertically lift and sustain said door through said lever and shaft while said lever extends straight up therefrom, resist the door-checking action of said spring means, and thereby prevent the pawl from being moved by said spring means to door-checking position.
- 10 5. A machine element comprising a lever with a circular hub aperture, a hollow cylindrical hub fitted in said aperture a non-circular tube fitted within said hollow cylindrical hub, and metal consolidating the lever, hub and tube, solidified from the molten state between said consolidated parts.
- 15 6. A machine element as recited in claim 5, wherein the non-circular tube is square in section.
- 20 7. A machine element as recited in claim 5, wherein the non-circular tube comprises a flat sheet of metal bent by fitting a hollow non-circular bushing within a hollow cylindrical hub portion and securing the three parts together by the use of metal solidified from the molten state while disposed between said flat sheet, hub portion and bushing, and a cable secured to said lever to, as long as it is taut, vertically lift and sustain said door through said lever and shaft while said lever extends straight up therefrom, resist the door-checking action of said spring means, and thereby prevent the pawl from being moved by said spring means to door-checking position.
- 25 8. The method of forming a machine element with a non-circular aperture in its hub comprising fitting a hollow cylindrical part in a corresponding aperture in the element to form an apertured hub for said element, fitting a corresponding non-circular tube within said hollow cylindrical part, and filling the spaces between the hollow cylindrical part, the tube and the element, with molten metal.
- 30 9. The method of forming a machine element with a non-circular aperture in its hub comprising fitting a hollow cylindrical part in a corresponding aperture in the element to form an apertured hub for said element, fitting a corresponding non-circular tube within said hollow cylindrical part, and filling the spaces between the hollow cylindrical part, the tube and the element, with molten metal.
- 35 10. The method of forming a machine element with a non-circular aperture in its hub comprising fitting a hollow cylindrical part in a corresponding aperture in the element to form an apertured hub for said element, fitting a corresponding non-circular tube within said hollow cylindrical part, and filling the spaces between the hollow cylindrical part, the tube and the element, with molten metal.
